UNITED STATES PATENT OFFICE.

FREDERICK W. RICHTER, OF ST. LOUIS, MISSOURI.

ELECTRIC PLUG AND SOCKET.

1,305,308.

Specification of Letters Patent. Patented June 3, 1919.

Application filed April 12, 1917. Serial No. 161,462.

To all whom it may concern:

Be it known that I, FREDERICK W. RICHTER, a citizen of the United States, residing at 5016 Von Versen ave., St. Louis, State of Missouri, have invented a new and useful Electric Plug and Socket; and I do hereby declare the following to be a full, clear, and exact description of the invention, such as will enable others skilled in the art to which

it appertains to make and use the same.

The invention is an electric attachment plug and portable lamp socket and seeks among its objects to provide improved electrical devices of this character.

A further object is to provide an electric attachment plug suitable for connection with the conventional plug base and having the contact shanks disposed in right angles to the length of the plug, whereby the strains imposed upon the flexible wire connected with the plug will be kept from exerting a direct pull upon the contact shanks.

A still further object is to provide in an attachment plug means for adjusting the contact shanks vertically, so that the distance which they project from the plug can be regulated as desired.

A still further object is to provide in an attachment plug means for changing the position of the contact shanks, so that the bottom of the plug may be kept pointed downwardly in case the base to which the plug is attached would otherwise tend to cause the plug to assume an inverted position.

A still further object is to provide an electric socket having an outer casing and a handling means integrally connected therewith, the casing having binding posts mounted on its interior which binding posts connect the socket leads with the conducting wires that transmit current to the socket.

A still further object is to provide in both the plug and the socket means for clamping the conducting cable in the casings thereof, so that the electric connection within each will be relieved of the physical strains imposed upon the cable.

Other objects will appear from the detailed description which follows.

Should the drawings and specification vary to the extent of having the one set forth some structure that is not fully defined in the other, the right is claimed to such structure as though it had been fully treated by both.

The drawings present the invention in one specific embodiment to which however it is not to be restricted. The right is reserved to vary the details of construction to any extent compatible with the spirit of the appended claim. A uniform system of designating the various parts of the invention obtains in all the figures of the drawings, wherein:

Figure 1 is an elevation of the improved socket.

Fig. 2 is a section on the line 2—2 of Fig. 1.

Fig. 3 is a section on the line 3—3 of Fig. 1.

The socket is a cylindrically shaped member, the upper end being of smaller diameter than the lower end to provide a means for conveniently handling the socket, as it is designed for particular use as a portable socket. The outer casing is divided in half longitudinally forming the portions 22 and 23 which are held together by straps 24 and 25 similar to strap 16 which is used on the cylindrical portion 4 of the attachment plug. The bottom part of the casing is hollowed out to receive those parts of the socket which carry the lamp. The shell 26 is provided at the top with an inturned annular flange 28 which lies against the flange 29 of a circular insulating piece (preferably porcelain) 30. Positioned centrally in the piece 30 is a contact stud 31 with a head abutting either base of the piece 30. The piece 30 further has an annular flange 27. Conducting wires 33 and 34 are soldered to or otherwise affixed to the stud 31 and shell 26 respectively and serve to conduct current to these parts by means of connections to be later described. The shell 26 and piece 30 are surrounded on their exterior by a suitable insulating material 32 which is adapted to be molded around these parts, the flange 27 serving to hold the piece 30 firmly positioned in this insulating material.

The wires 33 and 34 are surrounded by the insulating material 32 but these wires project far enough beyond this material to permit their attachment to the binding posts 35 fixed in the portion 22 of the outer casing. The handle portion of the outer casing is provided with a central hole, (formed half in the part 22 and half in the part 23) adapted to receive the flexible cord 1. This central hole is counterbored at the top to receive the spiral spring 36

which is in surrounding relation to the flexible cord 1 and relieves the latter of undue bending strains where it enters the outer casing. The lower end of the spring 36 is straightened and enters the hole 37 prepared for it in the upper end of the portion 23. The portion 23 is hollowed where it faces the binding posts 35, so as to provide room for the latter when the portions 22 and 23 are joined together. Wires 33 and 34 are connected each to one of the binding posts 35 where electric connection is effected with the wires 2, nuts 39 serving to secure the wires to the binding posts.

15 Diametrically opposite slots 40 are formed at the bottom of the outer casing and are centrally positioned with reference to the halves 22 and 23 thereof, these slots together with the divisions of the casing permitting the bottom end to be compressed (by the tightening of strap 25) on the insulating material 32 and to thus hold the socket portion securely within the casing. Similarly the tightening of the strap 24 25 operates to bring the two halves of the upper portion of the casing together and to firmly secure the flexible cord 1 therein, thus relieving the connections at the binding posts 35 from any strain that may be imposed upon the cord.

It will thus be seen that the construction relieves the connection between the binding posts and the socket from any strain and damage to these connections, is therefore, 30 reduced to a minimum.

Both the outer casing for the socket and the body of the attachment plug are designed to be made of hard wood, fiber or some other infrangible insulating material 40 and are, therefore, not easily broken.

With the attachment plug, the contact shanks 9 may be interchanged between either pair of diagonally opposite holes 8, so that the plug may be made to hang with 45 the cylindrical end 4 downward, whether the plug be attached to a plug base with contact holes disposed at an angle to the right or at an angle to the left of the perpendicular. Disposing the backs of the 50 contact shanks 9 at right angles to the body of the plug reduces to a minimum the liability of pulling the plug away from the

plug base to which it is attached, and any pull on the flexible cord 1 does not exert a direct pull on the shanks in the direction 55 of their length.

The outer casing for the socket is shown as having its two halves held together by the straps 24 and 25, but these straps might be omitted and the two halves of the casing held together by appropriate screws without departing from the spirit of the invention. The advantage of having the outer casing in two parts is apparent when it is remembered that the flexible cord attached to a portable socket often becomes soaked with grease and swells, thereby rendering it difficult to remove the solid casing.

The insulating material 32 is provided with an integral lug 41 adapted to engage 70 a recess in the portion 23 of the socket. This lug acts as an additional securing means for the insulating material 32.

What is claimed is:

The combination with a casing comprising 75 a pair of sections semi-cylindrical in cross section, the lower portions of the adjacent faces of said sections having semi-cylindrical recesses forming a chamber, said casing being constructed of non-conducting 80 material, of a porcelain member corresponding to and fitting said chamber, a locking connection between the porcelain member and the wall of the chamber, a metallic 85 socket threaded in the porcelain member, a porcelain plate in the upper end of the member, and provided with an electrical conducting pin, said casing having a handle portion provided with a longitudinally extending bore to receive electrical conducting wires, electrical conducting wires in 90 said bore, one connected to the conducting pin, and the other to the metallic socket of the porcelain member, and a pair of bands surrounding the two sections of the 95 casing separably connecting them together.

In testimony whereof I have signed my name to this specification in the presence of two subscribing witnesses.

FREDERICK W. RICHTER.
